UNITED STATES PATENT OFFICE.

ASA L. CORSON, OF PUEBLO, COLORADO.

PLACER-MINING MACHINE.

No. 909,553.

Specification of Letters Patent.

Patented Jan. 12, 1909.

Application filed July 6, 1907. Serial No. 382,530.

To all whom it may concern:

Be it known that I, ASA L. CORSON, a citizen of the United States, residing at Pueblo, in the county of Pueblo and State of Colorado, have invented a new and useful Improvement in Placer-Mining Machines.

The principal objects of my invention are, first, to provide a means of operating a placer mining machine in quiescent water; and second, to provide such means with a bathing screen for the purpose of washing particles of mineral from the sands; and third, to provide sets of amalgamating plates and troughs so arranged as to minimize the loss of any minerals; and fourth, to provide a receptacle, containing mercury or other amalgamating fluid, beneath said amalgamating plates and troughs, through which the sands must pass and thereby further prevent the loss of any minerals; and fifth, to provide a receiving tank beneath said receptacle, into which the minerals which escape the said plates, troughs and receptacle may pass and find lodgment, thus reducing the loss of minerals to a minimum.

I attain these objects by the mechanisms illustrated in the drawings heretofore filed, and the accompanying amended and additional drawings, in which—

30 Figure 1 is a perspective view of the machine in partial broken section exposing to view its several parts; and Fig. 2 is an end elevation of the slanting copper plates and troughs with their sweeping plates; and Fig. 3 is a side elevation of the sweeping plates showing the manner of mounting the same to be reciprocated to produce a sweeping movement on the slanting copper plates and troughs; and Fig. 4 is a perspective view of 40 a portion of the sweeping plates showing the manner of constructing the same; and Fig. 5 is a front elevation of the bathing screen and worm, with the front one half of the screen removed to expose the worm. Fig. 6 is a cross sectional elevation, in perspective, of the cast-iron receptacle, and the pair of agitating paddles that rotate with it. Fig. 7 is a central vertical sectional view through the whole apparatus.

50 Similar numbers refer to similar parts throughout the several views.

At the top of the inner rectangular casing 2, suitable bearings are supplied in which the pipes 3^a and 6 may rotate, the pipes 55 being rigidly attached to the end plates 6^a, Fig. 5, of the screen 4, and the worm 5 is

rigidly attached to the end plates 6^a, all forming a rigid mass that is rotated by means of the motor, gas engine, or other means, that may be belt connected by pulley 47 to pulley 46, which is rigidly attached to shaft 9 on one end of which the pinion 7 is attached, the latter meshing with large gear 8, that is attached to one of the end plates 6^a of the bathing screen.

60 Into hopper 3 mineralized sands or ores are fed and enter the bathing screen by gravity. The bathing screen is half submerged in the quiescent water within the casing, and the sands, immediately upon passing 70 into said screen become moistened. As the screen is rotated, the sands that are too large to pass through the mesh of the screen will be rolled along by means of the worm 5 till the opposite end of the screen is reached, 75 whereupon the lip 63, which must be rotated in the direction indicated by the arrow, Fig. 5, will gather it up and carry it up and above pipe 6 in such manner that the sand will fall by its own gravity along the dotted 80 line 64, Fig. 5, into pipe 6 and out of the screen. The rolling motion the sand has undergone by this operation, and its being passed through water, which fills the casing 85 1, has the desired effect to bathe the sand and jar loose from it any particles of mineral adhering to the sand.

85 The sand and mineral that passes through screen 4 will fall on slanting plates 15 and 15^a, Fig. 2, which are covered with mercury which will take up a part of the mineral, and the cup-like receptacles 56 at the lower edges of said plates are formed like the half of a tube with closed ends. These receptacles may be bent back under the 90 plates 15 and 15^a. They extend the full length of the plates and contain mercury over which the sands will pass before coming into contact with the mercury in receptacles 56. The troughs 16 are subtended 95 below plates 15 and 15^a in such manner that the sands pass over them and fall into said troughs which contain mercury in their bottoms. On the sides of the troughs 16 are receptacles 57, as shown in Fig. 2, which 100 are shaped like receptacles 56 on plates 15 and 15^a.

105 Sweep plates are provided to reciprocate along the upper surfaces of plates 15 and 15^a in such manner as to sweep the sands 110 along back and forth, and keep the same moving, and sweep plates 51 perform a

similar function in troughs 16. The sweep plates 50 and 51 are spaced apart by spacing pipes 58, Fig. 3, which surround rods 55, and are slideable through bearings 62 that 5 are attached to the inner sides of casing 2, and through suitable bushed holes in the back and front of casing 2. Rods 55 have upturned ends that enter suitable holes in angles 59, the latter being riveted at their 10 ends, to angles 60, the reciprocating motion being imparted to the sweep plates by means of pitman rods 48, which are pivotally attached to angles 60 at one end and to cranks 61 at the other, the said cranks being attached 15 to shafts 17 and 18 respectively. These shafts are driven from main shaft 9 by sprocket wheel 11, which is connected to sprocket 11^b on shaft 17 by chain 13, and sprocket 11^a is connected to sprocket 19 on 20 shaft 18 by chain 14. The upper sweep plates 50 and 51 are braced by brace 52 as are also the similar sweep plates 50 and 51 by brace 52 of the lower ones. The upper sweep plate 51 is connected to the lower 25 sweep plate 50 by brace 53. The slanting plates 15 and 15^a and troughs 16 are held up in place by rods 54, the upper edges of plates 15 being hooked over suitable hooks or screws in the side walls of casing 2.

30 The sweep plates are composed of plates 50^a and 50^b between which a suitable piece of belting 50^c is held in such manner as to admit the latter to rub on the slanting plates 15 and 15^a, or the sides of troughs 16, while 35 the plates 50^a and 50^b are held above said plates or troughs so as not to abrade the same.

The hopper 24 is attached at its upper sides to the four walls of the casing 2, and 40 its funnel shaped lower end enters down into receptacle 25 in such manner that the sands are fed down into the said receptacle. On suitable timbers across the top of hopper 24 that are secured to the end walls of casing 2, bearings are mounted that carry the shafts 21 and 27, and, on the former, the small bevel gear 23 is secured and meshes with gear 22 on shaft 27; and by means of sprocket wheel 20, which is secured to shaft 45 21, and chain 12 about sprocket wheel 10 on main shaft 9, a rotary motion is given to shaft 27 which carries casting 66, Fig. 6, on which agitating paddles 65 are mounted which are rotated inside of hopper 24, causing 50 a whirling movement in said hopper. The agitating paddles 28 are fastened to the hopper 24, and with it, remain stationary while receptacle 25, which is attached to shaft 27, rotates, and a whirling movement 55 is caused within receptacle 25, thereby causing the sands to be thrown out over the top of said receptacle; whereupon they sink, by their own gravity, to the bottom of the receiving tank 31, being guided by hoppers 29 and 30 and 32. On the bottom of shaft 27

a bearing 34 rotates over a cone bearing that is secured to the bottom of tank 31, and the arms 36 of bearing 34 carry the paddle arms 35 that rotate with shaft 27 stirring the sands in the receiving tank, thereby causing 70 the same to flow through opening 37 of the tank, and conduit 38 into a receptacle between casings 1 and 2, in which a bucket conveyer is mounted that serves to hoist the sands deposited there from tank 31 up and 75 out of the machine. The conveyer buckets are mounted on a sprocket chain 39 which travels over sprocket wheels 41 and 42, the latter being attached to shaft 43 that is driven by pulley 44, which receives its power 80 from pulley 45 on main shaft 9. In making clean ups of the minerals deposited in said machine, the water is drawn off by means of drain cocks 33 and 33^a, in Fig. 1. The doors of the inner and outer casing 68, 69 and 70, 85 are shown also in Fig. 1.

From the foregoing it may be seen that the several parts of my invention are driven by a motor that may be of any type, by means of a belt from pulley 47 to pulley 46, 90 the latter being attached to a main shaft 9, on which the several sprockets and a pulley serve to communicate power to operate the bathing screen, sweep plates, to rotate shaft 27 and its attached parts, and to operate the 95 bucket conveyer, the buckets on which are perforated so that the water will drain back into the casing, on account of the fact that the upward extending chute 49 is extended up a sufficient distance above casing 1 to admit of proper drainage from said buckets; all in such manner that mineralized sands fed into hopper 3 will first be screened and washed, throwing off the larger parts thereof, and the smaller parts passing through 100 the screen, down upon amalgamating plates that are arranged in series above each other to interrupt the course of the sands and cause the same to come into contact with the mercury on the plates, and in the receptacles 56 and 57 attached to them, and the receptacle 25 having mercury in its bottom 105 67, Fig. 6, serves to finally bring the sands into contact with mercury since all of the sands must pass down into the receptacle 110 56 and then upward and out over its top rim, while agitating paddles are vigorously stirring the sands, and the receiving tank 31 receives the sands that pass through the upper mechanisms together with any mercury 115 or amalgam that is washed past the several receptacles above.

The arrangement of the several parts herein described is such that the copper plates, receptacle, and receiving tank may be removed from within casings 1 and 2, where they may be cleaned of the mercury and amalgam contained in them; and for the purpose of removing these parts, suitable doors are provided in the casings 1 and 2 120 125 130

shown as 68, 69 and 70, Fig. 1. To drain off the water from the casings, suitable drain cocks, 33 and 33', Fig. 1, are provided in tank 31 and casing 1.

5 Having thus fully and accurately described my invention, what I claim as new and desire to secure by Letters Patent is:

1. In a placer mining machine, the combination with a rectangular casing within a 10 rectangular casing, adapted to contain a body of quiescent water, a worm containing bathing screen, agitating paddles and a perforated bucket conveyer for raising refuse 15 sands up and out of the machine, of slanting amalgamating plates and troughs, provided with receptacles for mercury, and that are provided with sweep plates, all arranged in such manner that sands falling from one set of plates will fall upon another set of such 20 plates or troughs, and thereby cause a further contact of the placer sands with other such plates containing mercury, substantially as and for the purpose set forth.

2. In a placer mining machine, the combination with a rectangular casing contained within another rectangular casing, adapted to contain a body of quiescent water, and a bathing screen, amalgamating plates and troughs, a rotating receptacle and a receiving 25 tank, of a rectangular casing means of retaining water and an arrangement therein of amalgamating plates and troughs in series with sweep plates above, a hopper, provided with agitating paddles, a rotating receptacle, a pipe conduit, a receiving tank in which agitating paddles are provided, and a bucket conveyer, all adapted to handle mineralized sands or ores to remove mineral 30 therefrom, and to dispose of the refuse 35 sands, substantially as described.

3. In a placer mining machine, the combination with a rectangular casing within another rectangular casing adapted to contain a body of quiescent water, amalgamating

plates, sweep plates, a receptacle provided 45 with agitating paddles, and a receiving tank from which sand is washed by agitating paddles, and a means of hoisting the sands up and out of the machine, of a rotating bathing screen containing a worm having a 50 lip means for delivering the sands through and out of the same, substantially as and for the purpose set forth.

4. In a placer mining machine, the combination with a rectangular casing within another rectangular casing adapted to contain a body of quiescent water, sets of amalgamating plates and troughs, sweep plates and a receiving tank, of a cone-shaped receptacle adapted to be rotated by a shaft and adapted 55 to contain mercury at its bottom, substantially as and for the purpose described.

5. In a placer mining machine, the combination with a rectangular casing within another rectangular casing adapted to contain a body of quiescent water, sets of amalgamating plates and troughs, a cone-shaped receptacle and a receiving tank, of a sweep plate means for agitating the sand in said water over said amalgamating plates and 60 troughs; and rotating paddle means of agitating the sands within a hopper; and stationary paddle means of agitating the sands within the rotating cone-shaped receptacle; and toothed agitating means on the lower 65 portion of a shaft within a pipe; and paddle means for agitating the sands in a receiving tank, all for the purpose of keeping the sands constantly agitated until the same have passed out of an opening in a tank, 70 substantially as described.

In testimony whereof I have signed my name to this specification in the presence of two subscribing witnesses.
